UNITED STATES PATENT OFFICE.

JOHN A. BELLMAN, OF HENRYETTA, OKLAHOMA, ASSIGNOR TO MINTON M. PAYNE
AND W. G. FLOURNOY, OF HENRYETTA, OKLAHOMA.

SPUDDING SHOE.

Application filed July 19, 1926. Serial No. 123,508.

This invention relates to spudding devices and more particularly to spudding shoes.

In the drilling of wells it is impossible to connect a drilling tool to the walking beam at the beginning of the operation, due to the length of the tool, and it is the usual practice to place the tool on a line from the bull wheel which is passed over the crown pulley of the derrick and connect this line to a jerk line by means of a spudding shoe, the other end of the jerk line being connected to the crank of the engine to produce an intermittent upward and downward movement on the main cable to which the tool is attached.

An object of the present invention is to provide a spudding shoe in which the cable is securely retained in the spudding shoe to prevent sliding of the shoe on the cable.

20 A further object is to provide a shoe having a spring pressed movable contact member adapted to engage the cable.

A further object of the invention is the provision of improved locking means for 25 the contact member which will prevent the shoe from becoming accidentally loosened on the cable but which may be readily released when desired.

In the accompanying drawings I have 30 shown one embodiment of the invention. In this showing,

Figure 1 is a front elevation of a part of a derrick diagrammatically illustrating the invention applied,

35 Figure 2 is a front view of the spudding shoe,

Figure 3 is a detail sectional view substantially on line 3-3 of Figure 2,

Figure 4 is a transverse sectional view 40 through a portion of the spudding shoe substantially on line 4-4 of Figure 2 showing the guides for the contact member, and,

Figure 5 is a perspective view of the contact member and operating arm removed.

45 Referring to the drawings, the reference numeral 1 designates generally a derrick having a crown pulley 2 arranged at the top thereof in the usual manner. The well drilling equipment is provided with the usual bull wheel 3 having a drum 4 mounted on its shaft over which is wound a cable 5. As shown, this cable extends upwardly and passes over the crown pulley, thence downwardly into the well being drilled. A

jerk line 6 is connected to the cable between the crown pulley 2 and the drum 4 and one end of the jerk line is connected to the crank 7 of an engine 8. The parts heretofore described are of the usual construction and form no part of the present invention except in the combination claimed.

At the other end of the jerk line I provide a spudding shoe 9 which is provided with a hook 10 at its rear end adapted to receive an eye or loop 11 on the end of the jerk line. The opposite end of the shoe is provided with a curved grooved portion 12 through which the cable is adapted to pass and the spudding shoe is adapted to be locked or fastened to the cable by means

of a suitable contact member. As shown (see Figure 4) the portion of the shoe between the hook 10 and the grooved portion 12 is U-shaped in cross section forming a base 13 and side walls 14. A cover 15 is secured to the side walls and forms a receptacle for the movable contact or shoe. As shown (see Figure 5) this contact is provided with a contact face 16 curved on an

arc substantially concentric with the curved portion 12 and the cable is adapted to be locked in the groove by frictional engagement with this contact face. At each side 75 the contact member is provided with upwardly extending arms 17 which are arranged adjacent the side walls of the casing when the device is in position (see Figure 2). The cover is provided with a pair

80 of inwardly projecting pins 18 arranged on its inner face adjacent the side walls and adapted to be received in longitudinal recesses 19 in the sides of the contact member to form a guide therefor.

85 Suitable means are provided for moving the contact member toward the groove portion 12 of the shoe and to permit its release. As shown (see Figure 3) the cover and body portion of the shoe are provided with a pair

90 of aligned openings adapted to receive a rod or pin 20. In front of the shoe this rod is extended at right angles forming a handle 21. Within the casing there is provided a finger 22 which is parallel to the handle and is turned downwardly to force the shoe toward the groove when the handle 95 is swung downwardly. The rear face of the contact member is provided with slots adjacent each end for the reception of the

ends of a leaf spring 23 and the end of the finger 22 is adapted to engage the central portion of this spring which is normally bowed as shown in Figure 5 of the drawings.

Suitable means are provided for retaining the actuating member in operative position. As shown, the outer side of the grooved portion of the shoe is provided with a stop 24 which is adapted to limit the movement of the handle. At right angles to the handle I provide a second finger 25 which is arranged in front of the cover. A spring plate 26 is fastened to the hook 10 and the lower end of this plate is provided with a finger 27 which is extended inwardly to engage the finger 25 as shown in Figures 2 and 3 of the drawings.

The operation of the device will be apparent from the foregoing description. In the drawings the locking member is shown in an operative position. Movement of the handle in a clockwise direction is prevented by the stop 24 and accidental movement in a reverse direction is prevented by the end 27 of the spring plate 26. To release the contact member from the cable the lower end 27 of the spring 26 is raised and the handle 21 swung through a quarter of a revolution in a counter-clockwise direction. This releases the cable and permits it to move in the grooved portion 12 of the shoe.

When the actuating member is moved to an operative position the finger 22 engages the spring and moves the contact member downwardly until the face 16 engages the cable. Further movement toward the position shown in Figures 2 and 3 of the drawings causes the spring 23 to straighten and thus impose an additional force on the contact member which effectually prevents the cable from slipping between the contact face 16 and the bottom of the grooved portion 12.

It is to be understood that the form of my invention herewith shown and described is to be taken as a preferred example of the same and that various changes in the shape, size, and arrangement of parts may be resorted to without departing from the spirit of the invention or the scope of the subjoined claims.

I claim:

1. In a device of the character described, a base having a curved portion adapted to receive a cable, a housing arranged on said base, a movable contact member arranged in said housing, a leaf spring mounted on the rear face of said movable contact member, an actuating member engaging said

spring, and means for attaching an actuating cable to said base.

2. A spudding shoe comprising a base having a grooved portion, a housing arranged on said base, a movable contact member arranged in said housing, a rod extending through said housing, a finger projecting from said rod and adapted to engage said movable contact member, a handle carried by said rod exteriorly of said housing, and a stop arranged in the path of said handle to limit its movement in one direction.

3. A spudding shoe comprising a base having a grooved portion, a housing arranged on said base, a movable contact member arranged in said housing, a rod extending through said housing, a finger projecting from said rod and adapted to engage said movable contact member, a handle carried by said rod exteriorly of said housing, a stop arranged in the path of said handle to limit its movement in one direction, and yieldable means to prevent movement in a reverse direction when said handle and rod are in an operative position.

4. A spudding shoe comprising a base having a grooved portion, a housing arranged on said base, a movable contact member arranged in said housing, a rod extending through said housing, a finger projecting from said rod and adapted to engage said movable contact member, a handle carried by said rod exteriorly of said housing, a stop arranged in the path of said handle to limit its movement in one direction, a finger carried by said rod exteriorly of said housing and arranged at an angle to said handle, and a spring arranged in the path of said finger to prevent movement of said handle and rod in a reverse direction.

5. A spudding shoe comprising a base having a grooved portion, a housing arranged on said base, a substantially U-shaped contact member arranged in said housing, the arms of said contact member being provided with recesses, pins carried by said housing and adapted to enter said recesses to guide said contact member, a rod extending through said housing, a finger projecting from said rod and adapted to engage said contact member, and a handle carried by said rod exteriorly of said housing.

6. A device constructed in accordance with claim 2 wherein a spring is arranged on the rear face of said movable contact member and is adapted to be engaged by said finger.

In testimony whereof I affix my signature.

JOHN A. BELLMAN.
